(57) CLAIM

The ornamental design for a dispensing device, as shown and described.

DESCRIPTION

FIG. 1 is a top, right, front perspective view of an embodiment of a dispensing device embodying our new design;
FIG. 2 is a right elevational view thereof, the left elevational view being a mirror image thereof;
FIG. 3 is a front elevational view thereof;
FIG. 4 is a rear elevational view thereof;
FIG. 5 is a top plan view thereof; and,
FIG. 6 is a bottom plan view thereof.

In a preferred embodiment, the nature of this product is a dispensing device for providing a liquid to a liquid sprayer that dispenses liquids from the rim of a toilet.

The broken line representations in the views are for illustrative purposes only and form no part of the claimed design.
